CLAIM

The ornamental design for an animal waste removal apparatus, as shown and described.

DESCRIPTION

FIG. 1 is a front elevation view of an animal waste removal apparatus.

FIG. 2 is a rear elevation view of the animal waste removal apparatus of FIG. 1.

FIG. 3 is a left side elevation view of the animal waste removal apparatus of FIG. 1.

FIG. 4 is a right side elevation view of the animal waste removal apparatus of FIG. 1.

FIG. 5 is a top plan view of the animal waste removal apparatus of FIG. 1.

FIG. 6 is a bottom plan view of the animal waste removal apparatus of FIG. 1.

FIG. 7 is an isometric view of the animal waste removal apparatus of FIG. 1; and,

FIG. 8 is another isometric view of the animal waste removal apparatus.

Portions of FIGS. 1 through 8 are shown in broken lines illustrating portions of the article that form no part of the claimed design.
